(57) **CLAIM**

The ornamental design for a coaxial cable connector, as shown and described.

DESCRIPTION

FIG. 1 is a front, right-side, top perspective view of a coaxial cable connector, the front, left-side, bottom perspective view being identical thereto;

FIG. 2 is a right-side elevational view thereof, the left-side elevational view being identical thereto;

FIG. 3 is a front elevational view thereof; and,

FIG. 4 is a rear elevational view thereof.

The broken lines depict environmental subject matter only and form no part of the claimed design.
